Japanese Patent Office's Publicly-known Material No. HC21004549 Catalog, "Marumi Filter Photo & Digital Accessories Catalogue", p. 1, accepted by the National Center for Industrial Property Information and Training on Apr. 10, 2009.

Primary Examiner — Philip S Hyder*Assistant Examiner* — John T Applewhite(74) *Attorney, Agent, or Firm* — Wolf, Greenfield & Sacks, P.C.(57) **CLAIM**

The ornamental design for a filter attachment for a camera, as shown.

DESCRIPTION

FIG. 1 is a front perspective view of a filter attachment for a camera showing my new design;

FIG. 2 is a rear perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof, the left side elevational view being a mirror image of FIG. 7; and,

FIG. 8 is a referential perspective of the filter attachment for a camera, wherein the broken line showing of the camera in FIG. 8 forms no part of the claimed design.
